The ornamental design for a spanner extrusion for connecting table legs, as shown and described.

DESCRIPTION

FIG. 1 is a perspective view of a spanner extrusion for connecting table legs showing a first preferred embodiment of our new design the center is broken away to disclose indeterminate length;

FIG. 2 is a top plan view thereof, the bottom plan view being substantially the same;

FIG. 3 is a front view in elevation thereof;

FIG. 4 is a rear view in elevation thereof;

FIG. 5 is a perspective view of a spanner extrusion for connecting table legs showing a second preferred embodiment of our new design, the front elevational view thereof being substantially the same as shown in FIG. 3 the center is broken away to disclose indeterminate length;

FIG. 6 is a top plan view of the second embodiment shown in FIG. 5, the bottom plan view being substantially the same; and,

FIG. 7 is a rear view in elevation of the second embodiment.
